SHIPPING CONTAINER FOR BOTTLES OR THE LIKE

Maureen L. Swanson, 6706 Hartman,
Omaha, Nebr. 68104

Filed Jan. 24, 1974, Ser. No. 436,347

Term of patent 14 years

Int. Cl. D9—03

U.S. Cl. D9—184

FIG. 1 is a top perspective view of a shipping container for bottles or the like showing my new design, the bottom being the same in appearance as the top;

FIG. 2 is a side elevation view, the opposite side being the same in appearance as the side shown;

FIG. 3 is an end elevational view, the opposite end being the same in appearance as the end shown;

FIG. 4 is a top plan view on an enlarged scale with the top removed;

FIG. 5 is a sectional view taken on the line 5—5 of FIG. 1; and

FIG. 6 is a sectional view taken on the line 6—6 of FIG. 1.

I claim:

The design for a shipping container for bottles or the like, substantially as shown and described.
